UNITED STATES PATENT OFFICE.

CHARLES G. THUNEN, OF OROVILLE, AND GEORGE A. MORRILL, OF OAKLAND,
CALIFORNIA.

LAMP-BRACKET.

973,319.

Specification of Letters Patent. Patented Oct. 18, 1910.

Application filed July 16, 1909. Serial No. 507,899.

To all whom it may concern:

Be it known that we, CHARLES G. THUNEN and GEORGE A. MORRILL, citizens of the United States, and residents, respectively, 5 of Oroville, in the county of Butte and State of California, and of Oakland, in the county of Alameda and State of California, have invented a new and Improved Lamp-Bracket, of which the following is a full, 10 clear, and exact description.

This invention relates to a new and improved adjustable lamp bracket, to be used on bicycles, motor cycles and the like.

An object of this invention is to provide 15 a device which will be simple in construction, strong and durable, and at the same time may be cheaply manufactured.

Another object of the invention is to provide 20 a device which will be adjustable, so as to be readily applied to either the head or handle of a cycle, and which will also be adjustable, to fit different sizes and styles of lamps.

These and further objects, together with 25 the construction and combination of parts, will be more fully described hereinafter and particularly set forth in the claims.

Reference is to be had to the accompanying drawings forming a part of this specification, 30 in which similar characters of reference indicate corresponding parts in both views, and in which—

Figure 1 is a perspective view, showing 35 the device attached to the head of a cycle; and Fig. 2 is a horizontal section of the device.

Referring more particularly to the separate parts of the device, 1 indicates a head bar of a cycle, on which a supporting member 2 is adapted to be clamped. The supporting member 2 consists of two parts, 3 and 4, which are preferably stamped of some suitable metal and have concave engaging portions 5 and 6, on the inner surfaces of which are secured suitable cushions 7 and 8, which may be made of any suitable material, such as rubber, felt or the like. The part 4 has, at the end, just beyond the concave portion 6, an extension 9, which extends at an angle thereto and has a plurality of perforations 10 therein, which are adapted to be engaged by a suitable hook member 11 on the other part 3 of the supporting member 2. By this means, the parts 3 and 4 55 may be adjusted relative to each other, so

as to engage securely, supports of different sizes. At the opposite end of the supporting member 2, the parts 3 and 4 are provided with facing concave portions 12 and 13, which form a socket for a suitable ball-end 60 14, which is preferably integral with a lamp-attaching member 15. The surfaces of the ball 14 and the engaging concaves 12 and 13 are preferably roughened or milled so as to grip each other firmly.

Intermediate the ends of the supporting member 2, there is provided on the part 3, an angular perforation, through which a suitable adjusting member 16, which is preferably in the form of a screw, is adapted to 65 70 pass. This screw 16 also extends through an alined opening in the part 4, and is adapted to clamp the parts 3 and 4 together by means of a thumb-screw 17, which is threaded onto the screw 16, and engages one 75 or more washers 18, interposed between the thumb screw 17 and the part 4. This screw-and-nut arrangement serves the double purpose of locking the supporting member to a support, and also of locking the attaching 80 member to the supporting member in any adjusted position, this relative adjustment being permitted by the universal joint or ball - and - socket arrangement, hereinbefore described.

The lamp-attaching member, at its end opposite to the ball 14, is preferably somewhat reduced, so as to form a lamp-engaging portion 19. To this part, there is pivoted by any suitable means, such as a rivet 90 20, a similar lamp - engaging portion 21. The portions 19 and 21 have suitable alined slots 22, which are adapted to receive an attaching member on the lamp. These slots, together with the side surfaces of the portions 19 and 21, are preferably milled or roughened, so as to form positive engaging surfaces. The purpose of having a plurality of portions 19 and 21, is in order that the attaching member may be adapted to readily 95 fit different styles and sizes of lamps which are provided with bifurcated lugs the tongues of which are separated from each other by varying distances in different styles of lamps.

While the device is shown as attached to the head bar of a cycle, it may just as readily be attached to the handle bar or any other portion of the machine, and inasmuch as there is provided a universal connection be- 100 105 110

tween the lamp-attaching member and the supporting member, the lamp is thus permitted to be held in its upright position, no matter to what part of the machine the bracket is attached.

Having thus described our invention, we claim as new and desire to secure by Letters Patent:-

1. In a bracket, the combination with a lamp-attaching member, of a supporting member, means for adjusting said supporting member relative to said attaching member, means for locking said members in any adjusted relation, and means for adjusting 15 the thickness of said attaching member to fit different lamps.
2. In a bracket, the combination with a lamp-attaching member having a slotted lamp-engaging portion, an auxiliary slotted lamp-engaging portion pivoted to said first-mentioned portion, a roughened ball-end on 20 said lamp-attaching member, a supporting member for said attaching member, said supporting member comprising two parts, each of which have facing concave portions 25 on one end which are adapted to form a socket to receive said ball-end, said parts of said supporting member having at their opposite ends concave support-engaging portions, cushions for said support-engaging 30 portions, means for adjusting said parts relative to each other, and screw-threaded means for locking said parts together.

3. In a bracket, the combination with a lamp-attaching member, of a supporting member comprising separable parts, one of 35 said parts having an extension with a plurality of perforations, the other of said parts having a hook adapted to engage any one of 40 said perforations to form an adjustable hinge joint, and means for adjustably securing said parts together.

4. In a bracket, the combination with a supporting member, of a lamp-attaching member comprising a roughened ball end, a 45 lamp engaging portion rigidly secured to said ball end and having a slot therein, and a lamp engaging portion pivotally secured to said first-mentioned lamp engaging portion and having a slot therein adapted to be 50 brought into alinement with said first-mentioned slot.

In testimony whereof we have signed our names to this specification in the presence of 55 the subscribing witnesses.
